REPEATING ATTACHMENT

Filed Nov. 17, 1922

2 Sheets-Sheet 2

UNITED STATES PATENT OFFICE.

HARRY LAWRENCE MILLER, OF ALLENTOWN, PENNSYLVANIA.

REPEATING ATTACHMENT.

Application filed November 17, 1922. Serial No. 601,609.

To all whom it may concern:

Be it known that I, HARRY L. MILLER, a citizen of the United States, residing at Allentown, in the county of Lehigh and 5 State of Pennsylvania, have invented certain new and useful Improvements in Repeating Attachments, of which the following is a specification.

My invention relates to the art of sound 10 reproducing instruments of the type wherein is provided a turn table having a spindle adapted to receive a record disk and a tone arm adapted to swing across the disk and carry a sound reproducer with a needle for 15 engaging the disk to reproduce the record made.

Primarily the invention has for its object 20 to produce a simple, inexpensive, neat and reliable device, and automatic in its action, for lifting the sound box needle off the record at the conclusion of the recorded matter and restoring the needle in contact with the sound groove of the record at its place of 25 beginning, over and over again, so long as the record disk is rotated by the turn table and the attachment is left in its operative position.

The invention essentially comprises an 30 element which is mounted on the record disk over the center post, a second element attached to the base of the machine and an intermediate element attached to the second element and adapted to be brought into operative relation with the first element by means 35 of a small adjusting arm moved with the sound box for operating a trip, mounted on the intermediate element and adapted to be moved into engagement with the rotating record disk, whereby the motion of the disk 40 will bring the intermediate element into engagement with that portion of the first element which elevates one end of the intermediate element and elevates the needle from the record to allow the sound box and 45 tone arm to return by gravity to the place of commencement.

In its more specific nature the invention furthermore resides in those novel details of construction, combination and arrangement 50 of parts, all of which will be first fully described, and then be specifically pointed out in the appended claims, reference being had to the accompanying drawings, which illus-

trate the preferred embodiment of my invention and in which:

Figure 1 is a perspective view illustrating the invention in use.

Figure 2 is a detailed elevation showing the invention in full lines in the playing position, the sound box and tone arm being indicated in light full lines at the commencement of the record, the dotted lines illustrating the position of parts when the sound box is being restored to the initial position, the arrow on the sound box indicating the direction of its travel under the influence of gravity.

Figure 3 is a top plan view of the invention in use.

Figure 4 is an enlarged top plan view and 70 part horizontal section showing in full lines the normal or playing position and in dotted lines the position which the intermediate element assumes when the trip has been actuated by the adjusting arm on the sound 75 box, the adjusting arm being indicated in dotted lines at the initial position and in dot and dash lines near the concluding position.

Figure 5 is an enlarged perspective view 80 of the first element or cam cylinder showing the commencement of the elevating cam and the termination of the lowering cam.

Figure 6 is a view similar to Figure 5 showing the termination of the elevating cam and the commencement of the lowering 85 cam and their relation to the lift groove at the top of the cam cylinder.

Figure 7 is a detail diagrammatical elevation of the adjusting arm showing the intermediate element in cross section and indicating by arrows the directions of the thrust.

Figure 8 is a detail perspective view of the adjusting arm.

In the drawings, in which like numerals 95 of reference designate like parts in all of the figures, 1 designates the first element which I shall hereinafter call the cam cylinder, (the form whether cone-shaped or straight is immaterial). Essentially the 100 cam cylinder comprises a body 1 on a base 2 which is apertured at 36, see Figures 3 and 4, to fit over the center post 37 of the turn table 38 of the phonograph. The cam cylinder 1 rests on the record disk 39, see 105 Figures 1, 2 and 3. The base of the cam

cylinder 1 is provided and formed with an upturned flange 3, thereby constituting a circular channel 4 for a purpose presently understood, and beginning in this channel 5 and extending upwardly and spirally around the body 1 of the cam cylinder is an elevating cam 5, 6, the entrant end 5 of which lies adjacent to the body 1 and extends upward from the groove 4 to its exit 10 end 6 which merges with the top spiral groove 7 on the upper end of the cylinder 1. A passage 8 is provided for a purpose presently understood.

The groove 7 has its beginning adjacent 15 to the body 1 where the upper end 6 of the elevating cam merges with the groove 7, the entrant end of the said groove 7 being nearer the center or axis of the cam cylinder than is its exit end 9. The exit end 9 20 is so arranged as to oppose the entrant end 10 of the descending cam 10—11, the discharge end 11 of which is spaced somewhat from the bottom of the channel or groove 4, see Figures 5 and 6.

12 is a screw standard which constitutes the second element of my device and it is provided with a head 13 by which it may be turned on its swivel bearing 14 in the base 15, the latter being secured to the base 30 of the phonograph, as best shown in Figure 1.

The intermediate member 17 consists of a light rod which is pivoted at 18 to a threaded body 16 mounted on the standard 12 and 35 susceptible of up and down adjustments. The other end of the intermediate member, hereinafter termed the intermediate arm, is bent at 19 to follow in general the curvature of the cam cylinder and is then bent 40 at 20 to extend in the general direction of the radius of the cam cylinder, the portion 20 terminating in a semi-circular head 21 which rides, normally, in the groove 4 in engagement with the flange 3 of the cam cylinder but which, when the intermediate arm 17 is moved inwardly (as will herein-after be described) will engage the entrant end portion 5 of the elevating cam and be thereby raised and delivered into the groove 50 7 around which it travels until it arrives at the exit end 9 of the said groove 7 when it will be delivered into the entrant end 10 of the descending cam and finally, at the end 11 of the descending cam, will be re-placed into the groove 4.

22 is a projection on the intermediate arm 17 on which is pivoted, at 26, a counter-weighted trip 23 having an arm 25 with a foot to engage under the rod 17, see Figure 60 1, in which position it is held by the over-balancing force of the vertical projection of the trip 23 and the horizontal finger 24 of the trip.

27 designates the adjusting arm which is 65 made in two parts 27—28 riveted together

at 29 in such a way that the part 28 will be held by retaining friction on the part 27 and held to allow for an adjustment of angle between the parts 27 and 28 to compensate for records of various lengths of production. The adjusting arm has an angled apertured portion 31 by which it is secured at 32 to the sound box adjacent to the needle socket. The underside of the adjusting arm 27 is rounded, as at 30, and is adapted to have sliding contact with the intermediate arm 17.

33 and 34 designate small apertures in the rod 17 in which a loop of wire 35 may be placed to establish the location of the sound box at the beginning of the record, be it a ten or twelve inch record, thus allowing the attachment to be used for both sizes of records. The sound box is indicated by the reference numeral 40 and the tone arm by 35 41 and the needle by 42. The construction of the phonograph proper, per se, forms no part of the invention, as they may be of the standard makes.

In the practical use of the invention if 90 it is desired to play a ten inch record the loop 35 is placed in the holes 33 and the end 21 of the intermediate arm 17 is placed in the groove 4. The adjusting arm portion 28 is adjusted so as to permit the needle 42 to continue to the end of the sound groove before the trip 23 is actuated. The needle 42 is then placed at the entrance to the sound groove in the usual way and the turn table started. The contact between the 95 adjusting arm 27 and the intermediate arm 17 during the transition of the sound box from the beginning to the ending of the record maintains the head 21 against the flange 3 of the cam cylinder until the adjusting arm portion 28 engages the trip 23 and rocks it from the full line to the dot and dash line position shown in Figure 2. The rocking of the trip 23 in this manner causes its foot to engage the record within 100 the inner portion where there are no sound grooves and the friction of such engagement causes the intermediate arm 17 to be moved from the full line to the dotted line position shown in Figure 4, thereby bringing 105 the head 21 into engagement with the body and into alignment with the entrance 5 of the elevating cam. The head 21 then rides up the elevating cam and is delivered into the top groove 7, at which time the intermediate arm 17 will assume the position shown in dotted lines in Figure 2 and causes 110 the sound box to slide, as indicated in dotted lines in Figure 2, back to the starting point. As soon as the end 9 of the groove 7 has 115 been reached the head 21 will pass down into the entrant end 10 of the descending cam and pass off the bottom of the same at 120 11 and back into the groove 4, thus freeing the head 21 from the cam and allowing it 125

130

to move back out of engagement with the flange 3 due to the pressure exerted by the weight of the sound box acting as indicated in Figure 7, thus restoring the needle 42 in contact with the record as shown in light full lines in Figure 2. This completes the cycle of operation of the attachment.

When it is desired to change a needle the operator need only lift the intermediate arm 17 to place the head 21 in the groove 7, (it of course being understood that the turn table at this time has been stopped) whereupon he may change the needle without swinging the sound box back away from the record and, upon starting the turn table again, the needle will automatically be brought to its initial position on the record at the commencement of the sound groove.

If it is desired to repeat a portion of a record the operator may, at any time, push the head 21 away from the flange 3 toward the body 1 of the cylinder and hold it there with his finger until the head 21 has been picked up by the ascending cam end 5 when the operation of restoring the needle to the beginning of the sound groove will be automatically conducted.

When it is desired to play the record in the ordinary way, without the use of the repeating attachment, the head 21 may be lifted out of the groove 4 and the attachment swung around the axis of the standard 12 to parallel the side of the cabinet and be out of the way.

In order to adjust the apparatus to the grooves of different records which, of course are not at the same distance from the center, the adjusting arm 28 is provided and it may be swung on its pivot 29 to any angle with regard to the arm 27 proper that may be necessary to compensate for the variations in the records.

While I have illustrated and described a preferred embodiment of my invention the same is capable of variations and modifications without departing from the spirit of the invention or the scope of the appended claims, and I therefore do not wish to be limited to the exact details of construction shown and described.

What I claim is:

1. A repeating attachment for disk phonographs, comprising a cam element having provisions to be set over the turn table spindle and turn with the same, a standard, an intermediate arm mounted on the standard and having a finger engaging said cam element, a trip on said arm, and means on the phonograph sound box to slidably engage said arm and adapted to engage said trip to set it into and out of contact with the record disk, said cam element having a circular bottom groove, and an ascending and a descending cam.

2. The combination with a sound repro-

ducing instrument comprising a rotating spindle, a record disk on said spindle and a sound box arranged to traverse said disk, of a bearing member for said sound box located in operative relation with said disk, a cam element mounted on said spindle and provided with connected elevating and depressing cam-ways, a trip on said bearing member, and means operable by said sound box for throwing said trip into engagement with the record to cause said bearing member to engage the elevating cam-way of said cam member.

3. The combination with a sound reproducing instrument comprising a rotating spindle, a record disk on said spindle and a sound box arranged to traverse said disk, of a bearing member for said sound box located in operative relation with said disk, a cam element mounted on said spindle and provided with connected elevating and depressing cam-ways, and means operable by engagement with the record and controlled by the sound box for bringing said bearing member into engagement with said elevating cam.

4. A repeating attachment for disk phonographs, comprising an element which is adapted to be mounted on the disk over the turn table spindle and rotate with the same, a second element attached to the base of the machine, an intermediate element attached to the second element and adapted to automatically engage with the first element, a trip on said intermediate element adapted to engage the record and thereby cause the engagement of the intermediate element with the first element, and means governed by the movement of the sound box for operating said trip, said first element having provisions for elevating the adjacent end of said intermediate element when the intermediate element is engaged with the first element, substantially as specified.

5. A repeating attachment for disk phonographs, comprising a member having a bottom circular run-way, a top spiral run-way and ascending and descending cam-ways cooperative with said run-way, a standard, an intermediate arm universally mounted at one end on said standard and having a projection to engage said first mentioned member in the run-ways and cam-ways of the same, means normally holding said arm in the bottom run-way out of engagement with the cam-ways of said first mentioned member, and other means for moving the free end of said intermediate arm to engage the elevating cam-way of said first mentioned member, substantially as shown and described.

6. A repeating attachment for disk phonographs, comprising a cam element adapted to be set over the turn table spindle of the phonograph and rotate with the turn table

and record, said cam element having a bottom circular run-way, an elevating cam-way and a descending cam-way, a standard, an intermediate arm universally mounted at one end on said standard and having its free end provided with a projection to engage in said circular run-way, means operating under the influence of the weight of the sound box for holding said free end against engagement with said elevating cam while the record is being played, and means operable by the motion of the record and controlled by the position of the sound box for bringing the free end of said intermediate arm into alignment with the ascending cam of said cam element.

7. A repeating attachment for disk phonographs, comprising essentially a cam element rotatable with the turn table, a fixed standard, an intermediate arm carried at one end by said standard and having the other end engaging said cam element, an adjusting arm movable with the sound box across the record and in engagement with said intermediate arm, and means controlled by said adjusting arm and operable by engagement with the record for bringing the free

end of said intermediate arm into elevating engagement with said cam element, at times.

8. In a repeating attachment for phonographs, a cam element adapted to be placed over the turn table spindle and on the record to turn with the same, said cam element having a bottom horizontal path, an elevating cam, a descending cam and a spiral groove from the exit end of the ascending cam to the entrant end of the descending cam, a standard including a screw, an intermediate arm universally mounted on said screw for up and down and lateral adjustments, the free end of said intermediate arm having a finger cooperating with said cam element, an adjusting arm movable with the sound box of the phonograph instrument and adapted to engage said intermediate arm to hold it out of the path of the elevating cam of the cam element, a trip on said intermediate arm and adapted to be engaged by said adjusting arm to itself engage the record and thereby move the free end of said intermediate arm to the path of the elevating cam on said cam element for the purposes described.

HARRY LAWRENCE MILLER.
